UNITED STATES PATENT OFFICE.

EMMET HORTON, OF ELMIRA, NEW YORK, ASSIGNOR TO HORTON BASKET MACHINE COMPANY OF WEST VIRGINIA.

BASKET-MACHINE.

No. 877,891.

Specification of Letters Patent.

Patented Jan. 28, 1908.

Application filed September 15, 1898. Serial No. 691,030.

To all whom it may concern:

Be it known that I, EMMET HORTON, a citizen of the United States, residing at Elmira, in the county of Chemung and State of New York, have invented certain new and useful Improvements in Basket-Making Machines, of which the following is a specification.

My invention relates particularly to machines for making baskets of wood veneer in which sheets of veneer are bent and secured by means of bands which encircle the upper edges of the bent sheets.

The primary object of my present invention is to produce a machine for making baskets of this class by automatic mechanism so organized and arranged as to cut the blanks for the basket from sheets of veneer, feed them forward to blank-bending devices, which bend them into form and which coöperate with band-applying mechanism that binds the upper edges of the blanks and completes the basket.

In carrying out my invention in the way now best known to me, I provide mechanism for feeding long strips or sheets of veneer to a cutter which severs the sheets into blanks of suitable size and shape to form the basket. The shaped blanks pass from the cutter to transferring devices which carry them to mechanism that bends and forms the blanks into final shape.

The transferring devices are so constructed and operated as to arrange two blanks cross-wise or at right angles to each other between a form and a former before the latter are brought into operation. The blank-bending mechanism comprises a series of sets of forms and formers mounted to move bodily about a common axis, while each form at the same time has an independent rotary movement about its own axis. When a pair of blanks is fed to a set of bending devices the form and former are separated, but immediately thereafter the former rises and presses the blanks around the form. After the bands have been applied the former recedes from the form and an expeller is operated which ejects the completed basket.

The band-feeding and applying devices at the proper time apply a band to the form before the blanks have been bent and also another band about the upper edges of the blanks before the completed basket is expelled; or a single band may be used which is first applied around the form before the ve-

neer blanks are bent and then wrapped around the veneer blanks after they are bent. Any suitable nailing devices may be employed to secure the bands in place. The mechanism is all driven from a common power shaft, and all the operations are continuous, it being necessary only for an attendant to feed sheets of veneer to the blank feeding table and to supply a bundle of bands from time to time to the band receptacle.

While I have stated the primary object of my invention to be to make baskets by automatic mechanism, my claims are not limited to mechanism wholly automatic. Some parts of the mechanism may be used without the others, and in machines differing from that in which I have shown them embodied. Thus, the mechanism for feeding the blanks may be used independently of the particular mechanism shown for forming the baskets, and the mechanism for forming the baskets and for applying the bands may be used with other forms of feeding mechanism. The details of construction in the feeding, forming, and band-applying mechanism may be considerably varied, the machine shown and described being simply one way of embodying my improvements.

In the accompanying drawings—Figure 1 represents a side elevation of a basket-making machine embodying my improvements, portions of the mechanism being shown in vertical section, and some of the parts being broken away the more clearly to illustrate other parts; Fig. 2 represents a plan of the machine, some of the parts being shown in section; Fig. 3 represents a transverse section of the machine looking from the front end thereof backwards, some of the mechanism being omitted as this figure is mainly designed to represent the cutter and the mechanism which operates it; Fig. 4 is a detail view in longitudinal vertical section designed to illustrate particularly the mechanism for feeding and cutting the blanks and for transferring them from the feed table to the bending mechanism; Fig. 5 is a detail view in perspective designed to illustrate particularly the construction of the delivery end of the feed table and the devices for transferring the blanks from the feed table to the bending mechanism; Fig. 6 is a view in perspective and on an enlarged scale, showing particularly the construction and illustrating the operation of the band-feeding mechanism;

Fig. 7 is a detail view in perspective of the main cam and gear wheel of the machine; it shows also one of the pinions driven thereby which conveys motion to the transferring devices, and another pinion which is connected to a shaft that operates the revolving frame carrying the several sets of bending devices which are employed; Fig. 8 is a view in perspective of a portion of the column which supports the rotary drum or frame carrying the bending mechanism; this figure also shows the lifting rod which operates to lift the formers and part of the mechanism which operates this rod; Fig. 9 is a detail view in section on the line y of Fig. 6; it shows particularly a guide-way for the bands secured to one of the forms or upper shaping dies; Fig. 10 is a perspective view of the basket made by the machine; Fig. 11 is a view in perspective of a portion of the column which supports the rotary drum or frame carrying the bending mechanism; this figure also shows the lifting rod which operates to lift the formers and part of the mechanism which operates the rod. It also shows a ball-way in which anti-friction balls are arranged to support the rotary drum or frames carrying the bending mechanism. Fig. 12 is a perspective view of the slide pinion and part of its connections which operate the mechanism for feeding the veneer blanks; Fig. 13 is a perspective view of the opposite side of the slide pinion; Fig. 14 is a detail plan view on an enlarged scale of the band tension arm or guide; it shows also the manner of attaching the arm to one of the arms of the frame which carries the bending mechanism; Fig. 15 is a detail view in side elevation of the same; Fig. 16 is a detail plan view of the transferring frame which conveys the lower blanks from the feed table to the bending devices; Fig. 17 is a side elevation of the same.

A standard, B, mounted on a base plate or bed, A, is provided with bearings, B', for the main driving shaft, a, which carries at one end a belt-pulley, b, and at its opposite end a pinion, c. The standard, B, is also provided with bearings for one end of a longitudinal shaft, 1, the opposite end of which is journaled in bearings, a', just in front of the column, 9, which supports the frame of the bending devices. A beveled slide pinion, d, is secured to the end of the shaft, 1, in front of the standard, B, and a wheel, 2, with a cam groove, 2', is secured to the shaft, 1, in rear of the standard. A blank supporting and feeding table, 6, is supported on Y-shaped standards, E, on opposite sides of the machine, and this table is provided with vertical flanges or sides, 26, between which sheets of veneer are fed to a knife, 3, which cuts them into proper length for and forms the baskets. The knife, 3, is attached to a vertically reciprocating cross-head, 7, bolted to vertical rods, 5, which slide in brackets,

g, g', located respectively on the table, 6, and on the bed plate, A. The rods, 5, are secured below the table to a cross-bar, 4, provided with a stud, e, carrying a roller, f which projects into the cam groove, 2', of the wheel, 2. As the cam wheel is revolved by the shaft, 1, the knife, 3, is reciprocated vertically at proper times to cut the blanks from the sheets of veneer.

The blanks are indicated in the drawings by letters, X and Y. The knife operates over and into an opening, h, in the table, immediately beneath it and those portions of the veneer which are severed from the blanks pass out through this opening. A large main cam and gear wheel, 8, is mounted on a transverse shaft, m, having bearings in the standards, E, and is provided with a circular unbroken series of teeth, 8', meshing with the pinion, c, on the end of the main power shaft, a. This wheel is continuously driven in the direction indicated by the arrow and gives motion to the different parts of the mechanism, as will be further on explained. A beveled series of teeth, i, on the inner side of the wheel, 8, meshes with the slide pinion, d, on the front end of the shaft, 1, and gives motion at the proper times to said pinion and shaft. Rotation of the pinion, d, except at the proper times, is prevented by a flange, d', on the wheel, 8, which engages at times with one of the straight edges, d'', of the headed end of the pinion, d. The teeth, i, it will be observed, extend only part-way around the wheel, 8. Two series of teeth, n, on the wheel, 8, are adapted to mesh with a slide pinion, 19, on a shaft, 21, mounted in bearings on the standards, E, just above the bed plate and below the shaft, m. On the left-hand end of the shaft, 21, is secured a crank wheel, o, provided with a crank pin, o', to which is connected a pitman, 22, that is also jointed at its opposite end to a crank arm, 22^a, secured to the lower end of a vertical shaft, 23, mounted in a lower bearing, 36', rising from the bed plate and an upper bearing, 36, formed on an arm, 36^b, projecting from the column, 9.

An oscillating movement through the arc indicated by dotted lines in Fig. 2 is given to the arm, 22^a, by the pitman, 22, and the shaft, 23, gives an oscillating movement to a frame, 24, which is adapted to receive the lower blanks from the feed table and transfer them to the bending devices. This frame 24, comprises an arm, 24', a transverse plate, 24^a, having a rearwardly projecting extension, 24^b, and upwardly projecting flanges, r. The teeth, n, on the wheel, 8, are adapted to give a one-half revolution to the pinion, 19, and this pinion is prevented from turning except when actuated by the teeth, n, by means of a flange, 20, on the wheel, 8, that engages in a recess, 20^a, in the side of the pinion. The upper blanks are fed to the

bending mechanism by means of horizontally sliding bars, 27, arranged on opposite sides of the table, 6, outside the flanges, 26. These bars have headed rear ends, 27', which are 5 provided with plates, 27', on their lower ends which project inwardly towards each other and which are adapted to support and carry the upper blank. The plates are arranged a little above the plane of the table, permitting 10 the lower blanks to pass beneath them, while the upper blanks are fed to them by means of stationary wedge-shaped pieces, 29, attached to the table just in front of the plates and in rear of the cutting mechanism. A link or 15 pitman, 25, is jointed to the frame, 24, and also to a cross-bar, 6^a, arranged beneath the table, 6, and provided with flanges, 6^b, secured to the bars, 27. The organization is such that as the vertical shaft, 23, is oscillated the transferring frame, 24, will be moved 20 through an arc of 90° and will feed the lower blank, X, into the position shown by dotted lines in Fig. 1; that is to say, with its longitudinal axis in line with the longitudinal axis 25 of the table. The bars, 27, however, move back and forth in straight lines longitudinally of the table and feed the upper blank, Y, without turning it and deliver it in the position indicated by dotted lines in Figs. 1 and 30 2. The mechanism is so arranged that the knife or cutter, 3, operates while the transferring mechanism is at rest.

After the blanks are severed and fed to the transferring devices the cutter remains stationary and the blanks are fed to the bending mechanism while the latter is stationary, the blanks being separated or removed from the transferring devices by the formers, 11, which rise at the proper time for this purpose. Any 35 suitable mechanism may be employed for feeding the sheets of veneer towards the cutter and to the transferring devices.

I have shown an upper pressure roller, M, mounted in bearings in the flanges, 26, of 40 the table, 6, and also pressure wheels, N, rigidly secured to a shaft, N', mounted in bearings in hangers, N^a, depending from the table. On one end of the shaft, N', is secured a flanged wheel, 33, and a crank arm, N^b. The crank arm carries a latch, n', and a stud or pin, 34. The stud is arranged on one side of the flange of the wheel, 33, while the latch is arranged on the opposite side. When the crank arm is in its rearmost position 45 the latch and stud do not bind the flange but when the crank arm has moved forward, the latch and stud bind the flange and thus give motion to the wheels, N, and thus feed the material to the cutter. A pitman, 35, is secured to the end of the crank arm, 34, and it is also connected with a disk, 30, secured to a short shaft, s, mounted in bearings just below the table. A pinion, 30^x, is secured to the rear side of the disk, as shown particularly in Fig. 13. In its front face the

disk is provided with a transverse groove, t, which is undercut as shown and receives the headed end of a bolt or crank pin, 31. This crank pin is provided with a sliding collar, t^a, and with a screw-threaded end, t^b. A 70 sleeve, t^c, fits over the end of the pin between the collar, t^a, and the screw-threaded end, t^b, and on this sleeve fits the eye, 35^x, of the pitman, 35; the nut, t^d, screws onto the thread, t^e, and holds the parts in position. 75 By loosening and tightening the nut, t^d, the position of the crank pin in the slot, t, may be adjusted. A plate, T^e, is secured to the pinion, 30^x, or to the shaft, s, the disk, 30, pinion, 30^x, and plate, T^e, being in fact all 80 rigidly connected together with the shaft, s. This plate is formed with a grooved surface, t^f, which engages a track or rail, t^g, on the cam and gear wheel, 8, on opposite sides of the teeth t^h, the arrangement being 85 such that when the teeth on the pinion, 30^x, are not in engagement with the teeth, t^h, the plate, T^e, will engage with the rail, t^g, and prevent the pinion from turning, but when the pinion, 30^x, engages the teeth, t^h, the 90 plate, T^e, is free to revolve in the space between the ends of the rail. The object of this arrangement is to prevent the feed rollers from operating when not positively actuated to feed the blanks. 95

A sufficient number of teeth are provided in the segment, t^h, to rotate the pinion, 30^x, at such time and speed as to properly operate the feed-wheels, N. The action is an intermittent one, and material is fed forward 100 to a sufficient extent to supply each time enough material to form two blanks.

The column, 9, mounted on the rear end of the bed-plate is hollow and is provided with a ball-way, 9^a, in which antifriction 105 balls or rollers, 9^b, are arranged to support a cylindrical frame, C, which carries the blank bending mechanism. This frame, C, is shown as formed with a central cylindrical flanged portion, c; from which project laterally upper and lower arms, D, D'. In the present instance I have shown six upper radial arms, D, and a corresponding number of radial arms, D', arranged directly beneath the corresponding upper arms. Around 110 the lower arms, D', is secured an annular rack, 13, having bevel teeth that gear with a bevel pinion, K, on the shaft, 1. By this means rotary motion is given to the frame, C, and this motion is an intermittent one, 115 inasmuch as the shaft, 1, to which the pinion, K, is secured is driven by the pinion, d, that meshes with the mutilated teeth, i, on the cam and gear wheel, 8. The lower arms, D', are provided with bearings, J, for vertically sliding rods, j, that carry the formers, 120 11. Each of these rods, j, is provided with a feather, 56, sliding vertically in a slot, j', in the bearing, J, by which arrangement the rods, j, are allowed to reciprocate vertically 130

but are prevented from rotating, when depressed, but are permitted to rotate when elevated.

The column, 9, is provided with a track, 12, of the form shown in Fig. 8, on which the lower ends of the rods, *j*, rest. The major portion of the track, 12, is straight and at such an elevation as to hold the formers, 11, at the limit of their upward movement so as to, 5 surround the forms, 10. The forms and formers act as dies to shape the baskets. The cut-away or depressed portion, 12^x, of the track is about two-sixths of the circumference of the column, and when the rods, *j*, rest on this portion of the track, the formers, 11, are withdrawn from the forms, as indicated on the left-hand side of the column in Fig. 1. A shoulder, 12^y, is produced where the cut-away portion, 12^x, joins the upper 10 portion of the track at the left-hand side of the machine, and close to this shoulder is a vertically sliding lift rod, 14, which is mounted to move in a hole in the column, 9, in the central longitudinal axis of the machine. 15 This rod, 14, is periodically raised and lowered by means of a lever, 15, secured to a rod, 16, and extending through an opening, 150, in the column, 9. The rod, 16, is mounted at one end in bearings, 16^a, on the column, 9, 20 and near its opposite end in bearings, *b*^a, in the standard, B. At its extreme front end it carries an arm, 17, that bears against a cam track, 18, on the cam and gear wheel, 8. This cam track is so formed and is of such 25 length as to periodically and at proper times operate upon the arm, 17, to turn the rod, 16, and give proper motion to the rod, 14. The function of this rod is to raise the rods, *j*, from the lower portion, 12^x, of the track, 12, 30 to the upper portion thereof, and while thus raising the rods, *j*, the formers, 11, are raised, take the blanks from the transferring devices and bend them around the forms, 10, immediately after which the rods, *j*, pass on 35 to the upper portion of the track, 12, and are held there while the series of bending devices are revolved in the manner hereinafter described.

A cam and gear wheel, 37, is rigidly secured to the column, 9. It is, therefore, 40 stationary, while the frame, C, revolves. This cam and gear wheel is provided on its periphery with a series of sets of teeth, *w*, and *w'*, the set, *w'*, being greater in number than 45 the sets, *w*, and between the sets of teeth are a series of curved guide-ways, *w*². Each form, 10, is provided with a hollow upper portion, 10^a, into which projects a hollow boss, 10^b, depending from the corresponding 50 arm, D. Through the bore of this boss projects a hollow shank, 10^c, formed on and extending upwardly from the form, 10, and has within it a rod, 43^a, on the lower end of which is a disk, 43^b, normally fitting a circular recess, 43^c, in the bottom of the form. The

upper end of the rod, 43^a, has a knob, 43, rigidly secured to it and between this knob and a bushing, 43^d, just above the recess, 43^c, is interposed a spiral spring, 43^e, which normally holds the disk elevated within its recess. This disk acts as an ejector for the completed basket, as will be hereinafter described. 70

The upper end of the bore of the shank, 10^c, is flared a little, adapting it readily to receive 75 a plunger rod, 47^a, depending from a horizontal lever, 47, secured to a rod, 47^b, pivoted in standards, 47^c, rising from the column, 9, or rather from the cam and gear wheel, 37. Between its pivots and the plunger rod, 47^a, the lever, 47, is pivotally connected with the upper end of the rod, 46, which extends vertically and centrally through the column, 9, being guided near its upper end in a guide block, 46^a, and at its 80 lower end in a guide, 46^b, on the bed plate. The lower end of this shaft is provided with a vertical series of teeth, 46^c, which mesh with a pinion, 45^a, on a horizontal shaft, 45, just above the bed plate and mounted at one end 85 in a bearing, 45^b, on the bed plate, and at its opposite end in bearings in the column, 9. The shaft extends through the column and at its outer end carries a bevel pinion, 44, meshing with a segment of teeth, 44^a, on the 90 shaft, 23. The arrangement is such that when the shaft, 23, is oscillated, it operates the shaft, 45, and rod, 46, and consequently the lever, 47, which gives movement to the plunger, 47^a, that actuates the ejectors and 95 certain other mechanism hereinafter described. Each shank, 10^c, has rigidly secured to it at its upper end a pinion, 39, and a stop plate, 40. Each pinion carries an unbroken series of teeth and each plate, 40, is 100 of a general rectangular form but its four sides are slightly curved, as indicated, to fit the guide-ways, *w*², on the periphery of the cam and gear wheel, 37.

When the frame, C, is revolved the pinions at times engage with the teeth, *w* and *w'* on the wheel, 37, and when so engaged are rotated. The plates, 40, also rotate at this time, being permitted so to do by recesses, 40^a, cut in the periphery of the wheel, 37, 110 over the teeth, but when the pinions are out of gear with the teeth, *w* and *w'*, the plates fit the guide-ways, *w*², on the wheel, 37, and the pinions, and consequently, the forms, 10, are prevented from rotating about 115 their bosses, 10^b. The bands, Z, which secure together the blanks, X and Y, at their upper ends, are held in the reservoir, R, carried by an arm, 52, extending laterally from the stationary wheel, 37. A shaft, 53, 120 is arranged in the reservoir and carries a spirally arranged screw, 53^a, adapted to enter between the bands, Z, and feed them one at a time from the reservoir through a slot or opening, 53^b, therein. The shaft, 53, carries 125

on one end a pinion, 49^a, meshing with the teeth, 49, of a rack bar, 55, depending from the lever, 47. The rack bar is provided with a vertical slot to receive the end, 53^x, on the shaft, 53. This end of the shaft is flattened on opposite sides and is adapted to move freely up and down in the wider portion, 100, of the slot. It is also free to move freely up and down in the narrow portion, 101, of the slot when its flattened sides are arranged vertically, but the shaft cannot revolve in this portion of the slot; therefore the rotation of the shaft, 53, and the screw, 53^a, is stopped at the proper time, while the rack bar, 55, continues to move downward with the lever, 47, which further downward movement operates the plunger, 48, to force the band through the slot, 53^b, into the holding device, 80. A guide, 102, is provided on the end of the reservoir, R, for the rack bar, 55. Fig. 6 does not show the bottom of the rack bar nor the top thereof. The slot is, of course, closed at opposite ends of this bar.

As the lever, 47, is reciprocated vertically, it moves the frame, 55, up and down, and gives a rotary movement to the shaft, 53. When moving in one direction the shaft, 53, is operated to cause the spiral blade, 53^a, to feed forward one band, Z. When the shaft 30 revolves in the opposite direction the blade is moved backwardly in position to engage another band to be fed forward when the shaft is reversed. The blade, 53^a, feeds the bands to the slot, 53^b, and the bands are ejected from the slot by means of a plunger, 48, attached to the lever, 47. A follower, 75, is pivoted to the arm, 52, above the bands, Z, and at its lower end, 75^a, bears against the bands. The upper end of the 40 follower is weighted at 75^b, and this end is bent back out of line with the pivot, 75^c, so that the end, 75^a, will be kept always pressed against the bands. The follower may be turned back at any time to permit the attendant to place a new supply of bands in the reservoir.

A hook or band-holding device, 80, is secured to one side of each form, 10. The bands are delivered, one at a time, into this holding device by the plunger, 48, as indicated in Fig. 6. The band-holder projects a little above the top of the form, 10, and its upper edges are slightly flared, as most clearly shown in Fig. 1, to facilitate the entrance of the band which is delivered from above, as indicated in Fig. 6. Each form is also provided with an eccentrically pivoted dog, 50, one end, 51, of which projects through an opening, 50^a, in the side of the form, and its other end is pressed inwardly by a spiral spring, 50^b, which causes the end, 51, of the dog to extend through the slot, 50^a. The face, 50^c, of the dog is roughened or serrated, adapting it to engage and hold the band, Z, in the holder, 80. The top edge

of the end, 51, of the dog is slightly beveled away, as shown in Fig. 9, so that as the band is fed in to the holder the dog will be moved back against the force of the spring, 50^b, and the band will then move into place. After reaching its proper position it will be held securely by the roughened end of the dog. Any longitudinal strain on the band will be resisted by the dog, which will turn and clamp the band to prevent its dislodgment.

Each form is provided with what I call a band-tension arm or guide, 41. Each arm is pivoted at 41^a to an arm, D, and it is provided with a short, inwardly projecting portion, 41^b, and a long, curved, outwardly projecting portion, 41^c. This arm is curved part-way around the form, and is also inclined downwardly, as illustrated in Fig. 1. Its lower end is forked at 90, and carries a roller, 91. The bifurcated end of the arm is adapted to engage a band as it is delivered from the reservoir and to hold it while being wrapped around the form. The arms are carried around with the forms as they revolve about the central axis of the column, 9, and once in each revolution the arms are tipped and moved by means of a stud, 42, which extends downwardly from the stationary gear, 37. When thus moved the roller end of the arm, 41, is swung outwardly and away from the corner of the form in position to receive a band from the reservoir. After passing the stud, 42, the arm moves back into place and holds the band while the form is being revolved. A spring, 92, is employed for returning each wrapping arm to its normal position. An adjustable stop, 93, may be employed for limiting the movement of the arm, 41. This is shown in Figs. 14 and 15, and consists merely of a screw-threaded rod having a lateral projection, e, engaging the end, 41^b, of the arm.

Any suitable nailing mechanism may be employed. I have not illustrated the details of construction of any nailing mechanism, but have only indicated part of the mechanism which may be used for operating the nailing devices. The vertical rod, 46, carries a series of rows of vertically arranged teeth 64, which mesh with teeth on segments, 62, pivoted on the upper end of the column, 9. These segments are connected with rods, 63, which may, in turn, be connected with the nailing mechanism.

In order to control the operation of the machine I employ means for coupling and uncoupling the band pulley, b, with the shaft, a. The pulley, b, is loose on the shaft, a, while the clutch disk, P, is keyed thereto. A spring, 60, interposed between the clutch disk, P, and a collar, 61, on the shaft tends to move the clutch disk into engagement with the pulley so as to rigidly connect the pulley with the driving shaft. The head of the disk P, is grooved at p, and into this groove ex-

tend fingers, p' , secured to a shipping rod, 58, arranged horizontally in guides on the standard, B. The opposite end of this rod is provided with a block, 59, which engages a block, 59^a, on a vertical rod, 57, mounted in suitable bearings and carrying on its upper end a handle, 57^a. By operating the handle the shipper rod may be operated to couple and uncouple the pulley with the shaft. The details of construction of the clutch mechanism are unimportant. Any suitable devices for this purpose may be employed.

The operation of the mechanism, has already been indicated, but briefly stated it is as follows: The band reservoir, R, is provided with a supply of bands sufficient in number to make a certain number of baskets, and the feed table is fed with sheets of veneer. The cam and gear wheel, 8, is revolved in the direction indicated by the arrow in Fig. 1, and the feeding mechanism feeds forward the sheets of veneer under the cutter, 3, which forms the blanks, X and Y.

The mechanism for actuating the cutter and feeding the veneer is such that the feed of the veneer stops while the cutter is operating and after the cutter has operated the feed is resumed. One blank, X, to form one-half of the basket is received on the transferrer, 24, while a blank to form the other portion thereof is received on the plates, 28. The blank, X, is turned into position by the transferrer, 24; while the blank, Y, is not turned but is fed straight forward, both blanks being moved into position between the form and former, as indicated in Fig. 1. When in this position the transferring devices rest and the rod, 14, is lifted, causing the former, 11, to rise and press the blanks, X and Y, around the form, 10, which has previously had a band, Z, wrapped around it, as will be hereinafter explained. While each set of forms and formers is receiving a set of blanks the frame, C, is stationary. After a set of blanks has been received and bent around a form, the frame, C, is revolved, and while thus revolving the forms, 10, are revolved about their own axes, or about the bosses, 10^b, for the purpose of applying the outside band, Z, to the basket. It should here be stated that each form, 10, before it receives a pair of blanks, X and Y, has a band, Z, wrapped about it, which constitutes the inner band of the basket, and then the blanks X and Y, are bent around this band, and after being so bent the second or outside band is applied, or the same band bent a second time around the form outside the bent blanks, X and Y.

It will be observed that the reservoir of the bands, Z, is located just opposite the first arm D in the series of arms. In the present instance I have shown six forms and formers arranged equally distant about the column,

9. These forms may be said to take six different positions. These positions I have numbered No. 1, No. 2, &c. When a form is in position No. 1 it receives a band, Z, and when it moves from position No. 1, the pinion, 39, engages with the long series of teeth, w', and the band is wrapped around the form, the form being given three-fourths of a revolution when passing from position No. 1 to position No. 2. When the form arrives at position No. 2 it receives the blanks, X and Y, and stops there long enough to have the blanks bent around it by the corresponding former. This operation will also bend the blanks around the band which was applied to the form in position No. 1. When passing from position No. 2 to position No. 3, one-fourth of a revolution is given to the form and the first part of the nailing is done at position No. 3. After that one-fourth of a revolution is given to the form when passing from position No. 3 to position No. 4, and nailing is done at position No. 4. This operation is repeated until the form reaches position No. 6 where the last nailing is done. It will be observed that in passing from position No. 1 to position No. 6 the form has been revolved twice; the band was first wrapped around the form once before the blanks X and Y were bent around it, and by means of the teeth, w, between the positions 2 and 3; 3 and 4, &c., another revolution is given to the form which wraps the band around the outside of the blanks, X and Y, the band being nailed as fast as it is applied in this way. As soon as position No. 6 is reached, the former drops, and then the form proceeds to position No. 1, where the completed basket is ejected, and then the form is ready to receive a new band for a new basket.

The mechanism is so constructed and operated that the several movements take place at the proper times and in the proper order to perform the several operations successively and without interference. I have shown six forms and corresponding formers, 110 but any desired number may be employed, the gearing mechanism being properly changed to change the times of the movements of the different parts, to bring the mechanism into operation in the proper order. 115

I do not herein claim broadly a screw for feeding the bands or other parts of the basket, as this subject-matter is claimed broadly in my application No. 640,537, filed June 12, 1897. In that application the screw-blade 120 is arranged vertically and the bands are given a quarter turn in being fed, while in this application the bands are not turned over while being fed to the form.

I claim as my invention:

1. In a basket-making machine, a plurality of shaping dies arranged to travel collectively and bodily around a common cen-

ter, in combination with means for revolving the dies individually while moving bodily, substantially as described.

2. In a basket-making machine, a revolving frame carrying two or more pairs of shaping dies adapted to receive between them the blanks composing the body portion of the basket, in combination with means for feeding and placing said blanks cross-wise between the dies, and means for actuating each pair of dies relatively to each other.

3. In a basket-making machine, a revolving frame or support carrying two or more sets of shaping dies arranged and adapted to travel around a common center, in combination with means for periodically arresting the dies, means for feeding bands to the dies, a stationary feed table adjacent to the path of the dies, and means for feeding and crossing the blanks for the body portions of the basket in position to be operated on by the dies, substantially as described.

4. In a basket-making machine, the combination of a series of forms and formers arranged to revolve about a common axis, means for thus revolving the forms and formers, means for revolving each form about its own individual axis, and means for operating the formers.

5. The combination of a series of forms and formers arranged to revolve about a common axis, means for revolving each form about its own individual axis, means for operating the formers, and means for supplying blanks and bands to the forms.

6. In a basket-making machine, the combination with a series of dies arranged and adapted to travel bodily around a common axis, means for alternately stopping the rotation and travel of the dies, means for feeding the blanks composing the body portion of the basket to the dies, and means for feeding and applying bands to the inner and outer edges of the basket, substantially as described.

7. The combination of a pair of shaping dies, means for opening and closing them, a feed table, common means for feeding a pair of superposed sheets of veneer towards the dies, common means for cutting out of said sheets a pair of blanks for the body portion of the basket, means for separating said cut blanks, and means for conveying them to and placing them cross-wise between the shaping dies.

8. The combination of bending devices, a conveyer having a horizontally arranged seat or holder for a basket blank, means for moving said holder horizontally in the arc of a circle to convey a blank into position between the bending devices, and means for conveying another blank and placing it cross-wise of the first mentioned blank between the bending devices.

9. The combination of blank bending de-

vices, a feed table, a conveyer oscillating in the arc of a circle to convey a blank to the blank bending devices and another conveyer moving in a straight line to feed another blank thereto and place it between the bending devices cross-wise of the first mentioned blank.

10. The combination of the bending devices, the feed table, means for feeding the stock over the table, a knife for cutting the stock into blanks, the conveyer for the lower blank, the conveyer for the upper blank, the wedge-shaped blocks for separating the upper blank from the lower blank and for guiding the upper blank into position on the upper conveyer, means for moving one of the conveyers to feed a blank between the bending devices, and means for operating the other conveyor to move a blank to the bending devices and place it between them cross-wise of the first mentioned blank.

11. The combination of the revolving frame, a form carried thereby and adapted to revolve about its axis while being carried around the axis of the frame, and a pivoted wrapping arm the outer end of which moves toward and from the form for holding a band while being wrapped around the form during the rotation thereof.

12. The combination of a revoluble form, a wrapping arm for holding a band while being wrapped around the form during its rotation, and means for automatically tripping and opening the arm to receive a band.

13. The combination of a revoluble form, a pivoted arm the outer end of which is movable towards and from the arm, and which holds the band while it is being wrapped around the form during the rotation thereof, a roller carried by the arm for guiding the band and means for automatically feeding the bands successively to the arm.

14. The combination of a band-reservoir having a horizontally arranged bottom on which the blanks are arranged vertically, edgewise, a spirally arranged screw-blade engaging the bands, and having a horizontal shaft, means for operating the shaft to actuate the screw-blade to separate and feed the blanks forward, one at a time, a basket-form the axis of which is arranged at substantially right angles to the axis of the screw-blade, and means for directing each blank separated by the screw-blade to the form.

15. The combination of a band-reservoir, a spirally arranged screw-blade adapted to engage the bands, one at a time, to feed them forward, a shaft on which the screw-blade is mounted and which is provided with a squared or flattened end, a pinion on the shaft, a slotted frame into which the squared end of the shaft projects, and a rack carried by this frame engaging the pinions.

16. The combination of a band-reservoir having a horizontal bottom on which the blanks are arranged vertically, edgewise, a screw-blade engaging the bands and adapted to separate and feed them forward, one at a time, a horizontal shaft on which the screw-blade is mounted, means for operating the shaft, a follower feeding the bands beneath the blade, a form, the axis of which is arranged at substantially right angles to the axis of the screw-blade, and means for directing each band as it is fed from the reservoir to the form.

17. The combination of a reservoir having a horizontal bottom for supporting a series of blanks, and having a discharge opening for the exit of the blanks, a screw-blade in the reservoir engaging the blanks and separating and feeding them forward, one at a time, to the discharge opening, a horizontal shaft on which the screw-blade is arranged, means for operating the shaft, a form, the axis of which is substantially at right angles to the axis of the screw-blade, and a plunger for forcing the blanks through the discharge opening to the form.

18. The combination of a rotary form having a holding device for a band, a band-reservoir having a horizontal bottom for supporting the bands vertically, edgewise, a screw-blade arranged in the reservoir, a horizontal shaft to which the screw-blade is secured, a follower for feeding the bands to the screw-blade, and a plunger for discharging a band separated by the screw-blade, and causing it to enter the holding device on the form.

19. The combination of a rotary form provided with a band-holding device, a band-reservoir, a screw-blade adapted to separate the bands, one at a time, from the supply, a plunger for discharging the separated band from the reservoir and causing it to enter the holding device on the form, and a guide arm engaging the band while held by the band-holding device.

20. The combination of a revolving frame carrying shaping dies, blank feeding devices for feeding blanks to the dies while they are stationary, means for then causing the revolving frame to revolve about its axis, devices for causing the shaping dies to revolve after having received basket blanks and after the dies are closed, means for applying a band or bands to the inside and outside of the basket while the revolving frame is revolving and while the shaping dies rotate, and means for ejecting the completed basket after the form has completed a revolution and the basket has been completed.

21. In a basket-making machine, a pair of shaping dies, and means for opening and closing them, in combination with a feed-table, means for feeding sheets of veneer together towards the dies, means for cutting out

of said sheets a pair of blanks for the body portion of the basket, means for separating said cut blanks, means for conveying one of said blanks into position between the shaping dies, and an oscillating carrier for conveying the other blank and placing it crosswise of the first-mentioned blank between the shaping dies.

22. The combination of a pair of shaping dies, means for opening and closing them, a receptacle for body blanks, means for conveying a blank from the receptacle to the shaping dies, and an oscillating carrier for conveying another blank to the shaping dies and placing it crosswise of the first-mentioned blank between said dies.

23. The combination with a rotary form, of a band holding hook on the side thereof, and a pivoted spring-pressed dog extending from the form into the hook.

24. The combination of a rotary form, a band holding hook on the side of the form, means for feeding the band into said hook, and a dog movable about an axis parallel with that about which the form rotates, and which moves laterally into the hook to grip the band while in the hook.

25. In a basket making machine the combination of forming mechanism comprising a rotary form and a die, mechanism for conveying and delivering the body blanks of the basket to the form and for crossing them with their ends projecting beyond opposite sides of each other, means for feeding a band to the form, means for rotating the form to wrap the band around it and a band-holder through which the band is drawn while being wrapped around the form and which is movable independently of the bending mechanism for holding the band close to the bending mechanism and means for positively moving said band-holder.

26. The combination with a rotary form, of a band holding hook on the side thereof, a pivoted spring-pressed dog extending from the form into the hook, and a band-holder movable independently of the form but which travels back and forth during each revolution of the form about its axis and holds the band close to the form.

27. The combination of a rotary form, a band holding hook on the side of the form, means for feeding the band into said hook, a dog movable about an axis parallel with that about which the form rotates and which moves laterally into the hook to grip the band while in the hook, and a band-holder movable independently of the form but which travels back and forth during each revolution of the form about its axis and holds the band close to the form.

28. The combination of a form mounted to rotate about a vertical axis, a band holding hook on the side of the form, means for feeding the band into said hook, a dog extending

from the form into the hook and a band-holder movable independently of the form but which travels back and forth during each revolution of the form about its axis and 5 holds the band close to the form.

29. In a basket making machine, the combination of a rotary form, a die coöperating therewith to bend the body blanks of the basket to shape, means for feeding bands to 10 the form, means for rotating the form to wrap a band around it and mechanism for feeding body blanks of the basket to the form and die, said mechanism comprising means for

carrying a blank to the bending mechanism and separate means for placing another blank crosswise of the first-mentioned blank with its ends projecting beyond the opposite sides of said first-mentioned blank.

In testimony, that I claim the foregoing as my invention, I have signed my name in presence of two witnesses, this 3rd day of September, 1898.

EMMET HORTON.
